United States Patent Office

Des. 220,833

Patented June 1, 1971

220,833

PATIO FASCIA PANEL

Arthur E. Haskell, Downey, William N. Brummet, Burbank, and Robert Fitzgerald, Huntington Beach, Calif., assignors to State Industries, Huntington Park, Calif.

Filed Mar. 13, 1970, Ser. No. 21,901

Term of patent 14 years

Int. Cl. D25—01
U.S. Cl. D13—1

FIG. 1 is a perspective view of a patio fascia panel showing our new design; and

FIG. 2 is an end view thereof.

We claim:

The ornamental design for a patio fascia panel, as shown and described.
